UNITED STATES PATENT OFFICE.

ANGELO L. SORESI, OF NEW YORK, N. Y.

SURGICAL APPARATUS.

Application filed November 30, 1925. Serial No. 72,366.

This invention relates to surgical apparatus, and has for its primary object to provide certain important improvements in an apparatus of the character disclosed in my prior application for patent Serial No. 713,878, filed May 17, 1924, whereby the efficient operation of the apparatus and its general utility in the performance of various surgical operations will be increased.

More particularly, by means of my present improvements I propose to provide an apparatus which may be easily operated for the practically uninterrupted or continuous transfusion of blood and whereby the possibility of clotting or coagulation or any chemical modification or change whatever in the blood during transfusion will be precluded. In accomplishing this result, as in my prior application, I employ a flow controller having freely movable gravity seated ingress and egress ball valves. In my present improvements, as will be hereinafter described in detail, I provide an improved form of seat for these gravity movable valves whereby the contact of the metal valve ball with the metallic stop member is substantially confined or limited to a single point or line upon the spherical surface of the ball. I have found that this construction, while providing a fluid-tight closure when the valve is seated, practically renders impossible any clogging or coagulation of the blood or the accumulation of fibrin upon the surface of the valve ball.

Another important object of my present invention is to provide an improved means for mounting and supporting the flow controller so that it is impossible to arrange said controller in other than the correct position.

An additional feature of my improvements resides in simple and novel means for removably mounting or supporting a syringe and operatively connecting the same with the flow controller.

With the above and other objects in view, the invention consists in the improved surgical apparatus, and in the form, construction and relative arrangement of its several parts as will be hereinafter more fully described, illustrated in the accompanying drawings, and subsequently incorporated in the subjoined claims.

In the drawings, wherein I have illustrated one simple and satisfactory embodiment of my present improvements and in

which similar reference characters designate corresponding parts throughout the several views,

Figure 1 is a side elevation of the device; 60

Fig. 2 is a sectional plan view taken on the line 2—2 of Fig. 1;

Fig. 3 is a vertical sectional view;

Fig. 4 is a section taken on the line 4—4 of Fig. 3; 65

Fig. 5 is a detail enlarged sectional view of the egress nipple and ball valve of the flow controller, and

Fig. 6 is a similar view of the egress valve showing the valve ball at the limit of its 70 opening movement.

As herein shown, the several essential parts of the apparatus are removably mounted and arranged upon a suitable support, said support preferably embodying an elongated metal base 5 provided with integrally formed arms 6 and 7 respectively, the rear arm 7 being vertically disposed and provided on its upper end with a horizontal tubular extension 8 internally threaded as at 9 for a purpose which will be presently explained. 75

The other arm 6 has a forwardly extending horizontal portion 10, the end of which is upwardly extended and inwardly curved as at 11 and terminates in a concave seat 12. The horizontal part 10 of the arm 6 has a vertical opening 13 formed therethrough and at the upper end of said opening is formed with a slightly raised seat 14. 80

The base 5 at the rear end of the vertical arm 7 has a transversely extending groove or channel 15 formed in its upper surface. While, owing to the construction of this support for the parts of the apparatus, said support may be conveniently grasped and held in one hand while the apparatus is operated by the other hand, I have indicated in the accompanying drawings several ways in which the support may be detachably clamped and rigidly held upon a suitable table or board arranged between two beds. Thus, the under side of the base 5 intermediate of its ends may be provided with a threaded socket 16 to receive the upper end of a screw 17 disposed through an opening 19 in the base board 18. A suitable clamping nut 20 is threaded upon said screw for engagement against the under side of the board 18. 95

As an alternative clamping means the yoke shown at 21 may be employed, one arm of said yoke extending beneath the board 18. 100

105

110

18 and carrying the clamping screw 22 while the other arm of the yoke is positioned above the board and terminates in a curved part 23, the extremity of which is adapted 5 for engagement in the groove 15 of the supporting base 5, when said base is disposed at right angles to the length of the board. On the other hand, when the support is arranged longitudinally of the board 18 adjacent one 10 of its side edges, the curved part 23 of the yoke arm may then be engaged upon a rounded surface of the base 5 between the spaced arms 6 and 7 thereof, as illustrated in Fig. 4 of the drawings.

15 The essential parts of the apparatus include a flow controller. As herein shown, this flow controller consists of a body 24 preferably of cylindrical form. This body 24 is provided with a central longitudinally 20 extending bore or passage 25 having an enlarged and preferably flared or conically formed ingress end 26. At the juncture of the intermediate portion of said passage with said flaring ingress end thereof grooves 25 or channels 27 in the opposite sides of the body connect said ingress end 26 to the intermediate part of the channel 25 on opposite sides of the juncture point indicated at 28, said juncture point formed by the meeting 30 surfaces of the central part of the channel 25 and its enlarged end 26 constituting a valve stop.

The opposite or egress end of the channel 25 is counterbored or enlarged as at 29 to 35 provide a valve seat 30, and beyond said counterbore 29, the passage opening upon the end of the body 24 is flared or conically formed as at 31.

Each end of the controller body 24 is 40 exteriorly threaded to receive an interiorly threaded cap 32, each of said caps being formed with a flange to detachably retain a nipple 33 and 34 respectively in connection with the opposite ends of the controller 45 body. Each of these nipples has a frustro conical head 35 and 36 and the tapered peripheral surfaces of these heads have snug fitting contact within the flaring ends 26 and 31 respectively, of the liquid passage through 50 the controller body and are held in fluid and air tight engagement therewith by the threaded caps 32. The other ends of the nipples are suitably formed for the attachment of lengths of tubing 37 thereto, each 55 length of tubing being adapted for connection at its other end with a suitable needle, one of which I have indicated at 38.

The end of the nipple 33 opposed to the ingress end 26 of the passage 25 is counterbored as at 39 to provide the valve seat 40. The end of the bore of the other nipple 34 connected with the egress end of the passage 25 is enlarged or flared as at 41, the juncture of said enlarged end with the bore 60 through the nipple providing the valve stop

42. The nipple head is also provided with grooves or channels 43 connecting the flaring end 41 of the bore to the main portion thereof at opposite sides of the stop 42.

The gravity movable valve balls 44 and 70 45 operate in conjunction with the stops and seats 28 and 40 and 42 and 30 respectively, in a manner which will be presently more fully referred to. Normally, these valves are seated by gravity upon the lower 75 seats 40 and 30 respectively as shown in Fig. 3 of the drawings.

The nipple 34 is formed with an annular flange indicated at 46 which is of greater diameter than the opening 13 in the supporting arm 10 while the nipple 33 is not provided with such a flange. Thus, only the latter nipple can be positioned through the opening 13, which insures the correct arrangement or mounting of the flow controller with the gravity ball valves properly co-operating with their respective seats to control the ingress and egress of the liquid.

For the purpose of producing a substantially continuous and uninterrupted flow of the liquid through the controller from the lower tube 37 to the upper tube 37, I provide a syringe of suitable construction. As herein shown, this syringe consists of a cylindrical metal barrel 47 having a tapering longitudinal extension 48 on one end through which the small diameter outlet duct 49 is formed. The other end of the syringe barrel has a convex bead or flange 50 formed thereon adapted for seating engagement against the tapered or conical internal surface 52 formed in one end of a bearing member 51, the other end of which is of reduced diameter and is loosely interlocked as at 53 with one end of a hollow cylindrical nut 54. This nut is externally threaded at 55 for engagement with the threads 9 in the upper end of the extension 8 on the supporting arm 7.

A plunger 56 of suitable construction is 110 contained in the syringe barrel 47 and has a rod 57 connected thereto and extending through an opening in the outer end of the nut 54, said rod being provided with a suitable operating handle 58. A coil spring 59 115 surrounding said rod bears at one of its ends against the plunger 56 and at its other end against the end wall of nut 54. The body 24 of the flow controller is provided with a radially extending tapered opening 60 120 therein communicating at its inner end with the channel or passage 25 substantially midway of its length.

In mounting the flow controller and the syringe upon the support, the flow controller is perpendicularly positioned and the nipple 33 inserted downwardly through opening 13 in the arm 6 until the cap 32 is engaged upon the seat 14. The cylindrical body 24 of the flow controller will thus be 130

positioned against the concave seat 12 on the end 11 of the supporting arm. The syringe barrel 27 is now inserted through the opening of the arm extension 8 and the reduced tapering extension 48 on the end of said barrel is engaged in the tapered radial opening 60 of the controller body. The cylindrical nut 54 is then threaded into the extension 8 and the bearing member 51 is caused to exert a longitudinal pressure against the barrel 47, thus forcing the surface of the tapered outlet extension 48 of said barrel into tight frictional contact against the wall of the opening 60 and securing an air and fluid tight seal between the outlet of the syringe barrel and the body of the flow controller 24. The apparatus may now be detachably secured in a convenient position upon a supporting board or other base by any one of the several clamping means shown in the drawings.

In the use of the apparatus for the transfusion of blood, each of the tubes 37 is provided at its free end with suitable needles 25 for insertion in the veins of the donor and recipient, respectively. The donor's tube 37 is connected with the lower or inlet nipple 33 of the apparatus while the recipient's tube is connected with the upper or outlet nipple 34. It will now be apparent that when the operator or surgeon draws the piston 56 outwardly from the barrel 47 against the action of spring 59, a suction effect is created in the channel or passage 25 of the flow controller, such suction acts to hold the upper gravity seated ball valve 45 in close contact upon its seat 30 to prevent any possibility of the creation of a vacuum in the recipient's tube 37 which would withdraw blood from the vein of the recipient. Such suction effect at the same time lifts the lower gravity seated ball valve 44 and does create a vacuum within the donor's tube 37 so that blood is drawn from the vein of the donor 40 through the needle and into said tube and hence through the nipple 33 and into channel 25, the blood flowing from said channel through duct 34 into the syringe barrel 47. Preferably, this syringe barrel has a liquid receiving capacity of approximately 2 cc. It will be noted that the raising or lifting of the lower valve ball is limited by the upper stop 28. However, the holding of the valve in this raised position does not appreciably impede the flow of the blood which may pass freely around the valve ball and through the grooves or channels 27 at opposite sides of the stop 28 into passage 25.

Upon the release of the syringe plunger it is projected to its normal position in the barrel 47 by the spring 59 and thereupon the lower valve ball 44 instantly drops by gravity to the seat 40 and closes the ingress nipple 33 while the pressure of the blood expelled by the syringe piston 57 lifts the upper valve ball 45 against the action of gravity until it contacts with stop 42. The blood is thus forced under pressure through passage 25 around the valve ball 45 through the grooves or channels 27 into the recipient's tube 37, from which it is finally expelled under pressure through the bore of the needle 38 into the vein of the recipient. It will be noted that in the construction of the several parts of this apparatus and particularly of the passages, chambers or cavities through which the blood flows, sharp corners forming pockets in which the blood might collect and stagnate are eliminated. Since all parts of the apparatus are perfectly air-tight, it is also apparent that no air can be drawn into the passages or channels thereof in the operation of the syringe so that absolutely whole unmodified blood is transferred from the vein of the donor to the vein of the recipient. Since these passages through which the blood flows are very accurately formed in accordance with the vacuum producing action of the syringe, no voids or dead air spaces will be produced. The possibility of ebullition or churning of the blood in its flow which might, to some extent, modify its chemical analysis is eliminated. Owing to the instantaneous action of the gravity seated ball valves, such apparatus insures a practically continuous and uninterrupted flow of the blood from the donor to the recipient during the operation of the syringe. Further, it will be observed that due to the construction of the ball valve stops and the exceedingly limited area of contact between the stops and the peripheral surfaces of the respective valve balls, possible coagulation of the blood or the collection of fibrin upon such surfaces is obviated. Thus, there is no opportunity for a static condition to exist in any part of the apparatus and practically the only change which occurs from that naturally existing in the vein of the donor is that a pressure somewhat in excess of the natural pressure existing in the human body is impressed upon the flowing stream of blood as it enters the recipient's tube 37. This is necessary in order to overcome the natural pressure of the blood stream in the vein of the recipient and preclude any back pressure tending to impede the flow of blood from the recipient's needle. It is equally important of course, that there shall be no back pressure of the blood through the donor's needle connected with the lower tube 37, and this is insured by the instantaneous closing of the lower ball valve by the action of gravity upon the release of the syringe plunger. It will be understood that the tubes 37 are as short as possible so that the time elapsing between the withdrawal of blood from the vein of the donor and its admission into the vein of the recipient is reduced to a minimum, thus

avoiding any possible chemical modification of the blood which might result from an appreciable decrease in its temperature.

After the desired quantity of blood has been transfused from the donor's to the recipient's vein, the needles 38 are withdrawn and the syringe and the flow controller then removed from the supporting structure and their several parts disassembled and thoroughly sterilized. It will be appreciated that owing to the construction of the several parts, such thorough sterilization thereof may be easily and quickly effected.

In addition to the use of such an apparatus for the purpose of blood transfusion, it may obviously also be utilized for the more effective performance of numerous other allied surgical operations. Thus, I have used my new apparatus with marked success in the operations of auto-transfusion of blood, local infiltration, regional anaesthesia, hypodermoclysis, paracentesis, and thoracentesis, intravenous injection and blood perfusion. In certain of these operations, a plurality of injection needles are connected with the tubing from the egress end of the flow controller, while in others, only the injection needle is used, the tubing connected with the ingress nipple of the controller having its free end immersed in the liquid to be injected.

From the foregoing, the construction and manner of operation of the apparatus will be clearly understood. It will be readily seen that such an apparatus in cases of emergency can be quickly applied to use and operated by the surgeon without assistance. I have above referred to the barrel of the syringe as consisting of a metal cylinder, but it will be understood that if desired, a cylinder of glass or other transparent material may be used having metal heads applied at the ends thereof so that the liquid drawn into said cylinder may be visible. Also, while I have herein referred to a preferred construction of the several parts of the apparatus, it will nevertheless, be understood that the essential features thereof might also be embodied in various other alternative structures, and I accordingly, reserve the privilege of adopting all such legitimate changes as may be fairly embodied within the spirit and scope of the invention as claimed.

I claim:

1. In surgical apparatus, a fluid flow controller including a body member having a longitudinal bore therethrough and longitudinally spaced valve seats and stops at the opposite ends of said bore, ball valves arranged between said spaced valve seats and stops and normally seating by gravity on the seats and adapted to be moved under pressure from such normal positions into en-

gagement with the stops and said stops having fluid passages at the opposite sides thereof whereby the fluid may have ingress to and egress from said bore around the valve balls, each of said stops presenting a single annular line of contact with the surface of the valve ball.

2. In surgical apparatus, a fluid flow controller including a body member having a longitudinal bore therethrough flared at its opposite ends and provided with a valve seat at one end and a valve stop at its other end, said body having fluid passages at opposite sides of said valve stop for the ingress of fluid to said bore when the valve is engaged on said stop, ingress and egress nipples each having an end formed for engagement in one of the flared ends of said bore and said end of the ingress nipple having a valve seat and the egress nipple having a valve stop, and provided with fluid escape passages at opposite sides of the valve stop, and ball valves arranged between the seats and stops at the opposite ends of said bore and normally seated by gravity respectively upon the seat of the ingress nipple and the seat at the egress end of said bore and movable under pressure into engagement with the valve stops, each of said valve stops presenting a single annular line of contact with the surface of the valve ball, said body member having a transverse opening communicating with said bore between the valve seats thereof, and a syringe adapted for connection with said transverse opening.

3. In surgical apparatus, a fluid flow controller including a body member having a longitudinal bore therethrough, ingress and egress nipples connected with opposite ends of the body member, said nipples and the bore of the body member having spaced valve stops, valve balls movable between said stops, a support for the flow controller adapted to receive the ingress nipple, the egress nipple being provided with means to prevent the mounting of the latter nipple in the support, and a syringe adapted to be connected with the bore through said body member intermediate of said valve balls.

4. In surgical apparatus, a fluid flow controller including an elongated body member having a fluid passage therethrough, automatic gravity operating valves at opposite ends of said passage responsive to pressure impressed upon the fluid in said passage and permitting of the flow of the fluid through said passage in only one direction, a support upon which said body member is adapted to be mounted in a substantially perpendicular position, and said body member being provided with means at one of its ends whereby in the mounting of said flow controller on the support at opposite ends thereof may be distinguished from each other so that said controller may not be arranged in

an inverted position and the valves thereby rendered inoperative.

5. In surgical apparatus, a fluid flow controller including an elongated body member having a fluid passage therethrough and automatically acting ingress and egress valves at the opposite ends of said passage, said body member also being provided with a transverse opening communicating with 5
10 said passage, a support upon which said member is adapted to be mounted in a perpendicular position, a syringe having a barrel provided with an outlet extension on one end for insertion into said opening, and means 15 for adjustably securing the syringe barrel in position relative to the support and operating to force the outlet extension thereof into fluid-tight engagement with the wall of said opening and simultaneously fix the fluid 20 controller in position on the support.

6. In surgical apparatus, a fluid flow controller including a body member having a fluid passage therethrough and automatically acting ingress and egress valves at opposite ends of said passage, a support upon 25 which said body member is adapted to be mounted in a perpendicular position and said support having a bearing opposed to one side of said member, said body member also having 30 a transverse opening communicating with said passage, a syringe consisting of a barrel having an outlet extension at one end for engagement in said opening and a spring 35 pressed plunger operating in said barrel, and adjustable means on the support in which the other end of said syringe barrel is mount-

ed and whereby said barrel may be longitudinally moved to effect a fluid-tight connection between the outlet extension thereof and the wall of said opening and simultaneously 40 clamp the body member of the controller against said bearing on the support whereby the syringe and the flow controller are fixed in operative relation with each other on the 45 support.

7. In surgical apparatus, a support having a base provided with spaced upstanding arms, a fluid flow controller adapted to be perpendicularly positioned upon one of said arms and including a body member having 50 a fluid passage therethrough and automatic gravity acting ingress and egress valves at opposite ends of said passage, said arm also having a bearing against which one side of the body member is adapted to be engaged 55 and said body member being provided with a transverse opening communicating with said passage, a syringe removably mounted on the other supporting arm and having a barrel provided with an outlet extension at one end, and means for adjusting said syringe relative 60 to the latter supporting arm to force said outlet extension into fluid tight engagement with the wall of said transverse opening and simultaneously clamp the controller body 65 against the bearing of said first named supporting arm whereby the flow controller and the syringe are fixed in their relative operating positions with respect to the support.

In testimony that I claim the foregoing as 70 my invention, I have signed my name hereto.

ANGELO L. SORESI.
